United States Patent Office

Des. 179,739
Patented Feb. 19, 1957

179,739

VENT COVER FOR STAND PIPES OR THE LIKE

Durward C. McClelland, Houston, Tex.

Application January 3, 1956, Serial No. 39,547

Term of patent 14 years

(Cl. D58—26)

Fig. 1 is a front elevational view of a design for a vent cover for stand pipes or the like showing my new design;

Fig. 2 is a top plan view thereof;

Fig. 3 is a side elevational view thereof; and

Fig. 4 is a bottom plan view thereof.

What is claimed is:

The ornamental design for a vent cover for stand pipes or the like substantially as shown.
